FIG. 1

FIG. 3

FIG. 4

Inventor
Mathias B. Becker
Williams, Bradbury,
See & McCall Attys.

UNITED STATES PATENT OFFICE.

MATHIAS B. BECKER, OF CHICAGO, ILLINOIS.

PACKAGING DEVICE.

1,401,304.

Specification of Letters Patent. Patented Dec. 27, 1921.

Application filed April 20, 1921. Serial No. 462,885.

To all whom it may concern:

Be it known that I, MATHIAS B. BECKER, a citizen of the United States, and resident of Chicago, in the county of Cook and State 5 of Illinois, have invented a certain new and useful Improvement in Packaging Devices, of which the following is a full, clear, concise, and exact description, reference being had to the accompanying drawings, forming 10 a part of this specification.

My invention relates to packaging devices and more particularly to packaging devices consisting of straps and buckles.

My invention finds great utility when used 15 for packaging asphalt shingles and the like. Asphalt shingles, that is, shingles which are made of material consisting chiefly of asphalt, are comparatively pliable, and are susceptible to injury when bound in bundles 20 with twine or wire. The use of twine or wire for this purpose generally results in a substantial percentage of mutilated shingles, moreover the use of twine or wire is undesirable because shingles of the kind mentioned 25 dry out and shrink, thereby causing the twine or wire to become slack.

The objects of my invention are:

To provide a packaging device with which 30 a number of articles can be quickly bound together without attendant injury to the articles.

To provide a packaging device which is capable of minute readjustments without removing it from its position about the package, and

To provide a device of the class described comprising a belt of woven material, and a buckle, the buckle having means whereby it can be detachably secured to the belt.

These and other objects of my invention 40 will be more clearly pointed out as the following description progresses, reference being had to the accompanying drawings, wherein

Figure 1 is a perspective view of a package of asphalt shingles, the shingles being bound together by the improved packaging device of my invention;

Fig. 2 is a perspective view of a buckle 50 which forms a part of the packaging device;

Fig. 3 is an end elevation of the buckle, the buckle being shown in operative association with a suitable strap, and

Fig. 4 is a rear elevation of the buckle, the

buckle being shown engaging the ends of the strap.

Similar characters of reference indicate similar parts throughout the several views.

In Fig. 1, I have illustrated a bundle of 60 asphalt shingles which are designated by the reference character 10. The shingles 10 are piled upon each other in any desired quantity, as shown. A strap 11 is shown disposed about the shingles 10, its ends being secured 65 by a buckle 12. The strap 11 and buckle 12 embody the novel features of my invention.

The strap 11 is made preferably of coarsely woven material, and is of sufficient width to prevent it from cutting into the 70 shingles. The flexibility of a strap of this character permits it to be drawn tightly and snugly about a bundle, thereby securely holding the contents of the bundle together.

The buckle 12 preferably consists of a 75 single piece of wire, the wire being bent to form an open loop 13, as shown in Figs. 2, 3, and 4. The loop has an end bar 14, side members 15-15 and tangs 16-16, each of the tangs 16-16 being joined to a side member 15 by a portion 17 of the wire. The tangs 15 are pointed as at 18-18. The tangs 16-16 are disposed to lie across the loop 13, but are also bent away from the plane in which the loop is disposed, thus allowing 80 sufficient clearance between the sharpened ends 18-18 of the tangs and the bar 14, to permit the insertion of the strap 11 into the buckle. However, the space so provided for the insertion of the strap 11 is made small 85 enough to cause the strap to engage the sharpened ends 18-18 of the tangs 16-16 when an attempt is made to withdraw the strap from the buckle without carefully guiding it by the sharpened ends 18-18. 90

The strap 11 being formed of coarsely woven material, it will be understood that the tangs 16-16 may pierce and secure the strap to the buckle, the tangs entering into the interstices between the warp and weft. 95

For convenience, the two ends of the strap 11 will be designated by the reference characters 20 and 21, the two ends of the strap being interchangeable. In the drawings, the end 20 has been shown impaled upon the 100 tangs 16-16 and drawn down upon the tangs so as to rest against the portions 17-17 of the buckle. The strap is disposed around the shingles and its other end 21 is 105 also secured to the tangs 16-16. 110

It is apparent that the strap may be tightened about the shingles by simply pulling upon the end 21, the tangs 16-16 being so positioned that they will readily pierce the strap when the operator ceases to pull upon it. The tension of the strap will draw it down upon the tangs. This structure permits the strap to be tightened at any time to compensate for shrinkage of the shingles. 10 The package may be handled by the strap end 21, and when it is carried by this end, the weight of the package will cause the belt to tighten itself about the package.

In the operation of the device, either end 15 of the strap may be first detachably secured upon the tangs 16-16 of the buckle, and the strap disposed around the articles to be bound. The other end of the strap is drawn through the buckle until the strap is sufficiently tightened about the package. This 20 end of the strap is then guided upon the tangs 16-16, the tension of the strap drawing it down upon the tangs as hereinbefore described.

25 What I claim is:

A device of the class described comprising a belt, a single piece of wire pointed at both of its ends and bent to provide a cross bar (14), a pair of side bars (15-15) which

are parallel to each other and disposed at 30 right angles to the aforesaid cross bar (14), a pair of shorter cross bars (17-17) which are disposed in the same plane with said side bars (15-15) and said first mentioned cross bar (14) and in a straight line at right 35 angles to said side bars (15-15), the extremities of said wire being turned away from said shorter cross bars (17-17) to provide straight pointed tangs (16-16) which are disposed in a plane oblique to the plane 40 which includes the first mentioned cross bar (14), the side bars (15-15) and the shorter cross bar (17-17), the points of said tangs (16-16) lying to one side of, but closely adjacent to, said first mentioned cross bar (14), one end of said belt being impaled upon said tangs and lying against the aforesaid shorter cross bars (17-17), the other end of the belt extending under said first mentioned cross bar (14) from the side 45 thereof opposite said tangs and being also impaled upon said tangs.

In witness whereof, I hereunto subscribe my name this 14th day of April, 1921.

MATHIAS B. BECKER.
